[57] **CLAIM**

The ornamental design for a rake for golf course sand traps, as shown and described.

DESCRIPTION

FIG. 1 is a perspective view of the rake for golf course sand traps;

FIG. 2 is an enlarged right side elevational view of the rake for golf course sand traps, the left side elevational view being a mirror image thereof;

FIG. 3 is a front elevational view of the rake for golf course sand traps;

FIG. 4 is a bottom plan view of the rake for golf course sand traps;

FIG. 5 is a rear elevational view of the rake for golf course sand traps; and,

FIG. 6 is a top plan view of the rake for golf course sand traps.

The claimed design is shown broken away in FIGS. 1, 3 and 5 for ease of illustration.
